IRONING MACHINE

Application filed June 24, 1928. Serial No. 373,376.

This invention has for its object the provision of a simple and compact apparatus whereby a smoothing iron may be driven by power and manipulated in such a manner that the clothes or articles being ironed or pressed may be easily adjusted between the strokes of the iron. The invention is illustrated in the accompanying drawings and will be hereinafter fully set forth.

10 In the drawings:

Figure 1 is a sectional elevation of an apparatus embodying the invention,

Fig. 2 is a transverse section on the line 2—2 of Fig. 1,

15 Fig. 3 is a similar view on the line 3—3 of Fig. 1, and

Fig. 4 is an enlarged end view of the clamp by which the iron is carried.

In carrying out the invention, there is provided a housing 1 which may be of any suitable form and dimensions and may rest upon the floor or be secured upon some other fixed support. Upon the top of the housing 1 at one end of the same is mounted a rack 2 upon which the ironing board 3 is secured. The ironing board is of the usual elongated tapered form and is secured rigidly upon the upper arm 4 of the standard or support 2 so as to be firmly carried, and in order that

25 the support may be conveniently mounted upon the housing, the lower portion thereof is formed into a base 5 which extends substantially parallel with the upper arm 4 and in the same vertical plane therewith. This base member 5 is provided with an opening therethrough adapted to register with a similar opening in the top of the housing to receive the upper end portion of a pivot bolt 6, the head of which bears upon the upper

30 side of the base and the lower end of which extends into the housing and is equipped with a nut 7, an expansion spring 8 being coiled around the bolt between said nut and the top of the housing, as shown clearly in Fig. 1, so that a constant tension will be exerted upon the bolt to firmly retain the base and the ironing board support in a set position. Most generally the ironing board will

35 be disposed longitudinally of the housing, as will be understood upon reference to Figs.

1 and 2 of the drawings, but it is sometimes more convenient to have the ironing board disposed transversely of the housing and for this purpose the pivotal tension connection illustrated is employed. In order to set the board transversely of the housing, it is necessary merely to swing it about its pivot point, whereupon it will be frictionally held in the transverse position.

40 At the opposite end of the housing, a longitudinal slot 9 is provided in the top of the same and through this slot extends a rocking arm 10 which is fulcrumed between two brackets 11 secured to the top of the housing and depending within the same. To the upper end of the rocking arm 10 is pivoted one end of a push rod 12 which extends to a point above the ironing board and is there connected with the iron 13 which may be of any approved type and is illustrated 45 conventionally as an electrically heated iron. The iron is connected to the push rod by a clamp consisting of an upper sleeve 14 encircling the end of the push rod and secured thereto by a rivet or bolt 15 inserted diametrically through the sleeve and the rod. Below the rod the side portions of the blank from which the sleeve is formed are brought together, as shown at 16, and firmly secured 50 together by bolts and nuts, indicated at 17. The lower portions of the blank are then secured 55 to connect the iron to the push rod. When the bolts 17 have been tightened, the jaws 18 will be engaged firmly around the handle of the iron so that accidental detachment of the same cannot occur. To the lower end of the rocking arm 10 is pivoted a pitman 19 which extends longitudinally of the housing and is pivoted at its inner end to a crank disk 20 secured on the end of a transverse shaft 21. This shaft is mounted in any convenient bracket 22 within the casing and is equipped 60 at its rear end with a gear 23 meshing with a gear 24 on the rear end of a transmission shaft 25 which is disposed below the shaft 21 and is provided with a spur gear 26 at its front end. Said gear 26 meshes with a gear 65

70 75 80 85 90 95 100

27 on the driving shaft of a motor 28 which is preferably an electric motor and is illustrated conventionally. It will now be understood that the rotary motion of the motor shaft is converted into an oscillatory movement of the rocking arm 10 which, in turn, effects reciprocation of the push rod 12 so that the iron will be moved to and fro over the article placed upon the ironing board.

18 Adjacent the ironing board supporter 2, a standard 29 is erected upon the housing and this standard is vertically slotted at its upper end to receive and guide the push rod 12 and prevent lateral movement of the rod 12 so that the iron will be held to a rectilinear path. Preferably a roller, indicated at 30, is mounted in the standard below the push rod so as to aid in supporting the same and permit a free easy movement thereof while the apparatus is in use. Upon the extreme rearward stroke of the iron, the push rod 12 will be caused to bear upon the roller 30 so that the forward end of the rod will be raised and the iron thereby lifted slightly 25 from the ironing board so that the work may be adjusted to present a new surface to the iron.

30 Between the standard 29 and the rocking arm 10, a standard or bracket 31 is mounted upon the housing, and through an opening in the top of this bracket and a similar opening in the top of the housing is fitted a vertically movable bar 32 which is equipped at its upper end with a loop or bail 33 spanning 35 the push rod 12 and equipped with a roller 34 in its lower end. Mounted within the housing is a longitudinally extending rock shaft 35 which is provided with a crank arm 36 to which is pivoted the lower end of a link 37 which has its opposite end pivoted to the bar 32. If the shaft 35 be rocked so that the crank arm 36 is swung upwardly, the bar 32 will be raised and the roller 34 brought into contact with the push rod 12 so that the rod 40 will be lifted and the iron withdrawn from 45 the ironing board and supported in its raised position. A second crank arm 38 is fixed to the rock shaft 35 and a retractile spring 39 is secured to said arm and to the side of the housing, as shown most clearly in Fig. 2, so 50 that the bar 32 will be normally yieldably held in its lowered position so that it will not interfere with the movement of the push rod. To effect the upward movement of the 55 bar 32, a third crank 40 is provided upon the push rod and a handle link 41 is pivoted to said crank 40 and extends through the side of the housing, as shown clearly in Fig. 2, so that, if the handle member be drawn outwardly, the shaft will be rocked so as to 60 support the iron in a raised position. Any suitable means may be provided for holding the iron in the raised position against the action of the spring 39 to permit the com-

pleted work to be removed and fresh work substituted therefor.

It will be readily noted that we have provided an exceedingly simple and compact apparatus whereby a smoothing or pressing iron 70 may be driven by power over an article to be pressed and the manual labor connected with the ironing operation very materially diminished and so minimized that the work may be completed rapidly without fatigue 75 to the attendant.

Having thus described the invention, we claim:

1. In an ironing apparatus, a housing, an ironing board mounted at one end of the 80 housing, a rocking arm mounted at the opposite end of the housing, means for oscillating the rocking arm, a push rod pivoted to the upper end of the rocking arm, an iron carried by the push rod to move over the ironing board, a guide bracket on the housing, a vertical bar fitted through the top of the housing and said bracket for vertical reciprocation, a bail at the upper end of said bar spanning the push rod, a rock shaft within 85 the housing, and means whereby rocking of said shaft will raise or lower the vertical bar.

2. In an ironing apparatus, a housing, an ironing board mounted at one end of the housing, a rocking arm mounted at the opposite 90 end of the housing, means for oscillating the rocking arm, a push rod pivoted to the upper end of the rocking arm, an iron carried by the push rod to move over the ironing board, a rock shaft extending longitudinally of the housing, a crank projecting from said rock shaft, yieldable means for holding said crank normally in a lowered position, a vertical bar extending through the top of the housing and equipped at its upper end with a bail spanning the push rod, a link connecting the crank with the lower end of the bar and means for rocking the shaft.

In testimony whereof we affix our signatures.

TIMOTHY S. DAVIS. [L. S.]
